Patented Jan. 29, 1918.

UNITED STATES PATENT OFFICE.

OTHO M. OTTE, OF JAMESTOWN, NEW YORK.

DETACHABLE REFLECTOR.

1,255,039.

Specification of Letters Patent. Patented Jan. 29, 1918.

Application filed October 18, 1917. Serial No. 197,352.

To all whom it may concern:

Be it known that I, OTHO M. OTTE, a citizen of the United States, residing at the city of Jamestown, in the county of Chautauqua and State of New York, have invented certain new and useful Improvements in Detachable Reflectors, of which the following, taken in connection with the accompanying drawings, is a specification.

10 The invention relates to reflectors, and the object of the improvement is to provide a simple and easily attachable and detachable reflector surface for a shaft of light as, for example, a pad of white linen or canvas or some flexible material which has a strong reflecting surface either natural or coated with a reflecting material or capable of such a polish as will reflect a shaft of light from a reflector lamp as, for example, 15 a spot light on an automobile, the reflector pad being attached to the lining of the automobile top so that the light is reflected down upon the occupants of the vehicle, the easily detachable nature of the reflector making it 20 possible to move the same to different parts of said top so that the light may be more strongly deflected into certain portions of the vehicle; and the invention consists in the novel features and combinations herein- 25 after set forth and claimed.

In the drawings, Figure 1 is a perspective view of an automobile with the people therein and the top broken away partially so as to show the reflector attached to the under- 30 side of said top and the shaft of light from a spot light directed onto said reflector to deflect the light rays upon the occupant of the car. Fig. 2 is a plan view of said reflector showing the preferred shape and ar- 35 rangement of the same. Fig. 3 is a perspective view of the preferred form of the attaching hook, the hook being turned at right angles to the attaching cross bar; and Fig. 4 is an elevation of a modification of the 40 preferred form of attaching hook, the hook being in the same plane with the cross bar and having a spring snap to hold said hook in engagement after attachment. Fig. 5 is a plan view of a corner of the reflector be- 45 fore the attachment of the hook showing the hole for insertion of the hook and the folding flap for holding the hook in place.

Like characters of reference refer to corresponding parts in the several views.

50 The numeral 10 designates the body portion of the reflector which is preferably

made of flexible material such as white linen, canvas or other bendable material which can be rolled or folded with the top when in the knock-down position without injury to said reflector. It might, however, be made of thin bendable white opaque celluloid which takes a fine polish and would make a good reflecting surface, or any other bendable material which could be polished 60 or coated with a reflecting substance.

The reflector 10 is preferably made in the triangular form shown though it might be made oblong or round or elliptical in design without departing from my invention. 70 The triangular form is preferred for flexible fabrics like cloth since each of the three different sides can be drawn tight and straight in line eliminating all wrinkles and the reflector surface is flat and smooth. 75

The manner of attachment is very simple. A plurality of spaced flaps 11 are provided in the triangular form one at each corner is preferred, and in other forms a sufficient number to hold the fabric or other 80 material flat and straight as well as attach it firmly to its support. An opening 12 is provided in the material on the folding line of the flap or holding end 11, so that an anchor shaped hook 13 having a cross bar 15 85 may be inserted through the hole 12 and be held in position by folding the flap 11 back over the cross bar 15. Said hook 13 is preferably turned at an angle to the cross bar 90 15, that is, not in the same plane as shown in Fig. 3, though the hook 13 may be made as shown in the modified form in Fig. 4 in the same plane and serve a good purpose, a spring snap 14 being provided to hold the hook against withdrawal from the attach- 95 ing material whether leather or cloth or some other fabric. The shank 16 extends up through the hole 12 and it is apparent that when the flap 11 is attached to the body portion of the reflector 10 after being folded 100 against the same either by stitching or some other firm attaching means, the hook 13 at each corner or at spaced portions of the body portion 10 may be inserted in the supporting material as, for example, the lining 105 of an automobile top and being stretched firmly in place against the dark material of said automobile top forms a bright glistening reflecting surface against which the shaft of light from the spot light 17 may 110 be turned thereby deflecting said shaft of light upon the occupants of the car.

It is apparent that the reflector 10 is easily attached or detached from the cloth or fabric forming the lining of the automobile top and that it may be quickly removed 5 to any portion of said top and the position of the spot light 17 and the shaft of light therefrom changed so that it shines upon the reflector 10 in its new position. In attaching the hooks 13 they are preferably all 10 turned toward the side on which the flaps 11 are attached so as to present an uninterrupted reflecting surface on the other side which is the exposed side of the reflector. It is also obvious that it might be attached 15 in other ways than the one shown and attain my purpose though the construction would not be as strong and simple as the one shown.

I claim as new:—

- 20 1. The combination with a vehicle top, of a reflecting element attached to the underside of said vehicle top, and a lamp on said vehicle having a projecting reflector to project a light shaft upon said reflecting element 25 to deflect said light shaft upon the occupants of said vehicle.
2. A reflector comprising a piece of fabric having a reflecting surface, spaced flaps on said piece of fabric to fold and attach thereto, said fabric having a hole in the line of said fold and a hook having an anchor shaped shank to extend through said hole and be held by said fold.
- 30 3. A reflector for lighting the interior of an automobile embodying a reflecting ele- 35

ment, means to attach said element to the top of an automobile, said element being flexible so as to be capable of folding with and upon folding of the top and a spot light having means to attach same to the automobile for projecting light onto said element. 40

4. A reflector for lighting the interior of an automobile embodying a reflecting element, means to attach said element to the top of an automobile, and a spot light having means to attach same to the windshield for directing light upwardly at an angle onto said element. 45

5. A reflector for lighting the interior of an automobile embodying a fabric reflecting element of substantially triangular form, and hooks for securing the element to an automobile top, said hooks having anchoring means and the apices of the triangular-shaped element being wrapped around said anchoring means of the hook. 50

6. A reflector for lighting the interior of an automobile embodying a reflecting element, means for attaching said element to the top of an automobile, and a spot light having means of attachment to the automobile for projecting light onto said element with the rays projected in paths above the line of vision of the occupants. 60

In testimony whereof I have affixed my signature in the presence of two witnesses.

OTHO M. OTTE.
